UNITED STATES PATENT OFFICE.

HENRY B. FABER AND HARRY E. SEAL, OF NEW YORK, N. Y., ASSIGNORS
TO RUBBER BALLOON COMPANY OF AMERICA, OF NEWARK, NEW
JERSEY, A CORPORATION OF NEW YORK.

RUBBER BALLOON-BAG.

No. 824,071.

Specification of Letters Patent.

Patented June 19, 1906.

Original application filed February 4, 1904, Serial No. 192,007. Divided and this application filed May 20, 1905. Serial No. 261,459.

To all whom it may concern:

Be it known that we, HENRY B. FABER and HARRY E. SEAL, citizens of the United States of America, residing in the borough of Brooklyn, city and State of New York, have invented a certain new and useful Improved Rubber Balloon-Bag, of which the following is a specification.

This invention comprises a rubber toy balloon-bag formed in a single piece, without a seam, and of peculiar novel shape.

In the accompanying drawings, Figure 1 is a view in elevation, showing a mold upon which the balloon-bag may be formed. Fig. 2 is a view, also in elevation, of one of the bags when removed from the mold. Figs. 3 and 4 are views in elevation, showing balloon-bags similar to Fig. 2 in different stages of initial inflation. Fig. 5 shows a balloon inflated to proper size, the scale being somewhat reduced.

The manner of making the bag is as follows: The mold A, which may be substantially oval or egg-shaped in form, is preferably made of glass. Other suitable material, such as hard rubber, may be used. The mold is provided with a stem or handle B, of reduced dimensions, extending from its top, and upon the lower part of which, ending about line e e, is formed the neck b of the balloon-bag, which is provided with a reinforce-strip at the edge b'.

The mold is constructed with a small tapering or conical protuberance or teat c, springing from the bottom thereof and which may be round, square, or polyhedral and is best placed with its apex coincident with the longitudinal axis of the mold, although it may be somewhat displaced, the purpose being in dipping that the apex of the cone shall first enter and last leave the solution.

C, Fig. 2, indicates a balloon-bag removed from the mold, c being the extension formed by cone a.

D, Fig. 3, shows the bag slightly inflated, the extension c being somewhat expanded

and flattened. E, Fig. 4, shows further inflation of the bag and greater expansion of the extension c, and F, Fig. 5, indicates, on reduced scale, a fully-inflated balloon in which the extension c has become obliterated.

In using the mold it is dipped into the solution, then withdrawn, inverted, and the deposited coating dried. This operation is repeated until the desired thickness of rubber is deposited upon the mold, after which the reinforcing-strip is applied at the edge b, the bag vulcanized on the mold and stripped therefrom.

The balloon-bag so produced and shown in Fig. 2 is oval or egg-shaped, with a teat or projection at its bottom. Experience has shown that such shape is suitable and practicable for the result sought. It is not, however, intended to exclude such departure from that shape as may be adopted without impairment or material impairment of the usefulness of the bag for the purpose intended. Seamless balloon-bags formed, as described, with an extension c are characterized by the fact that the rubber in respect to thickness and denseness or homogeneity forming the extension is uniform with the other parts of the bag. This is a condition not ordinarily attainable when a seamless bag is made without such extension.

The mold herein described is disclosed and claimed in our Letters Patent No. 790,491, dated May 23, 1905, of which the present case is a division.

We claim as our invention—

A seamless rubber balloon-bag, having an egg-shaped body with a tapering extension on the bottom and adapted to be inflated to spherical form.

In testimony whereof we have hereunto subscribed our names.

HENRY B. FABER.
HARRY E. SEAL.
